CLEANING AND POLISHING APPARATUS

James F. Waters, New York, N. Y.

Application August 4, 1945, Serial No. 608,851

2 Claims. (Cl. 15—124)

1

This invention relates to apparatus for cleaning, rubbing and otherwise treating floors or other surfaces.

Among the objects of the invention is to provide an apparatus whereby floors may be cleaned or rubbed at the will of an operator. Another object of the invention is to provide an apparatus having cleaning equipment including one or more brushes and polishing equipment including one or more pads and which are so related to one another that the cleaning equipment or the polishing equipment may be brought to bear upon a surface whereby, depending upon the manual setting of the apparatus, either cleaning or polishing may be accomplished.

Other objects and advantages of the present invention and what I now consider the best mode of applying the principle of the invention will be hereinafter set forth in the accompanying specification and claims.

In the drawings,

Figure 1 is a transverse section through the apparatus;

Fig. 2 is a horizontal section on line 2—2 of Fig. 1;

Fig. 3 is a vertical section taken longitudinally through one end of the apparatus at line 3—3 of Fig. 1; and

Fig. 4 is a perspective view of the apparatus.

The body portion or frame of the apparatus consists of a casing 10, which may be made of metal, plastic, wood, or any other suitable material. The underside of the casing is open and accommodates the cleaning and polishing equipment. These equipments are so mounted in the casing as to be selectable for performing their respective functions. In the embodiment of the invention illustrated in the drawings, the polishing equipment is fixed with respect to the casing, and the cleaning equipment is displaceable from a position of non-use to a position of use, and vice versa. When one of these equipments is in its position of use the other equipment is in a position of non-use. The particular equipment which is readied for use rests upon the surface to be treated and it is therefore preferred that the cleaning equipment be displaceable so that the bristles of the brushes thereof will not be subjected to the weight of the apparatus when the apparatus is stored.

The polishing equipment includes two pads, a wet pad 11 for applying wax or oil, and a dry pad 12 for polishing or rubbing. Pad 12 is carried on the underside of a backing member or holder 13, which is supported from a longitudinally ex-

2

tending member 14, which is fastened at its ends to the end walls 15 and 16 of the casing. A pair of rails 17 and 18 extending downwardly from the longitudinally extending member 14 serve to hold the backing member and attached pad in position against the underside of the longitudinally extending member 14. The construction is such that the backing member can be removed and replaced by sliding it lengthwise longitudinally of rails 17 and 18. The backing member is dovetailed for receiving the edges of the pad which are clamped by a wire or other fastening means. Wet pad 11 is similarly attached to the underside of a longitudinally extending member 19, which is notched at its side edges for engaging the pad and bent edges 20, 21 of the casing. The backing member 19 and its attached pad can be removed from the apparatus by sliding the same lengthwise of the bent edges 20 and 21. The lower surfaces of the two pads 11 and 12 are in the same plane for together bearing upon and rubbing a surface to be treated, such as a floor.

Member 19 is slotted at 22 to permit the application of oil or wax to the back of pad 11. Conduit 23 is provided for distributing liquid material along the back of the pad from a number of spaced apertures 24 opening from the underside of the conduit. This conduit has a T connection 25 with a valve 26 through which connection may be made with a receptacle 27. By means of a handle 28 the amount of fluid material delivered to conduit 23 and to pad 11 can be controlled, at will. The pads may be made from felt or from any suitable absorptive materials such as are customarily used for polishing and rubbing. Receptacle 27 may be made a part of the casing with the end walls and one side wall of the casing constituting vertical walls of the receptacle. A partition 29 inside the casing serves as the other vertical wall. The bottom wall of the receptacle is in the form of a dished plate 30 to which the T connection is attached.

The cleaning equipment preferably consists of two brushes, 31, 32, which are mounted against the lower surface of a vertically displaceable carrier 33. The carrier is contained in compartment 34 of the apparatus. Unless held in a depressed position in which the ends of the bristles of the brushes extend below the under surfaces of the pads, the carrier is maintained in an elevated position as shown in Fig. 1, by a pair of springs 35, 36. The ends of these springs are engaged by the fixed longitudinally extending member 14, and by cups which are fastened to the movable

carrier 33. Four angle members 37, 38, 39 and 40 are attached to the carrier and serve to prevent the carrier plate from tilting crosswise of the casing.

The carrier has extending upwardly from its ends a pair of brackets 41, 42 (Fig. 2) whose outer surfaces provide sliding contact with the end walls 15 and 16 of the casing and together with angle members 37, 38, 39, and 40, maintain the carrier horizontally disposed. These brackets also serve to transmit to the carrier the action necessary for depressing the carrier and its brushes to locate the scrubbing portions of the bristles below the pads.

Each bracket has a pin 43 laterally extending from its upper end and engaging in a slot 44 at the end of an arm 45 of a bell crank lever. This bell crank lever is pivoted on a stud 46 which extends from the end wall of the casing. The other arm 47 of the bell crank lever has a projection 48 laterally extending from its end. The bell crank lever at each end of the casing is normally disposed, as illustrated in Fig. 4, when the brushes are out of position for their use.

The apparatus is provided with a handle 49 which is attached to a bail 50 having arms 51, 52 extending to opposite ends of the apparatus. Each of these arms is similarly engaged to rotary bushings 53, 54, respectively. The bushings are mounted in the end walls 15 and 16 of the casing. As shown in Fig. 3, the lower end of arm 51 is bent to provide a shaft 55, which is engageable with the bore 56 of bushing 53. Shaft 55 is keyed to the bushing so as to rock the bushing when the handle 49 is moved from a position extending from one side of the apparatus (Fig. 1) to a position extending from the other side of the apparatus. An annular removable boss 57 is fastened by a screw 58 to the end of bushing 53 within the casing. This boss carries an arm 59 by which bell crank lever 45-47 may be actuated. Arm 59 is so formed as to remain out of operating engagement with the bell crank lever when it is desired to use the apparatus with the pads 11 and 12 bearing on the surface to be treated, as illustrated in Fig. 1.

When it is desired to depress the brushes below the pads and to engage and bear upon the surface to be treated, it is necessary only that the operator swing handle 49 across the top of the apparatus to the right hand side as viewed in Fig. 1. Such action will cause the curved end of arm 59 to engage projection 48 on arm 47 of the bell crank lever. Continued motion of the handle to a convenient position for moving the apparatus over a surface causes the cam surface 60 to engage projection 48 and thereby rock the bell crank lever to depress the carrier and its brushes. The end of the cam surface of arm 59 emerges into a circular arc and functions to hold the brushes below the pads even though the angularity of handle 49 varies somewhat as the operator pushes the brushes over a supporting surface. Consequently, when the brushes are in use the effect of springs 35 and 36 on arm 59, and hence on casual swinging of handle 49 does not vary. A hook 61 at the end of arm 59 prevents the arm from over-running stop 48. While I have described the bell crank lever and arm which is located at one end of the apparatus, it will be understood that this carrier-operating mechanism is duplicated at the other end of the apparatus, as shown in Fig. 2, so that both ends of the carrier will be simultaneously controlled by the handle.

Brush 32 is provided for applying cleaning fluid to the floor. This cleaning fluid may comprise carbon tetrachloride, kerosene, caustic soda, or any other material suitable for cleaning purposes. For distributing the cleaning material to the floor, a longitudinally extending conduit 62 is provided. This conduit has a plurality of openings 63 at its lower surface through which cleaning fluid is dropped to the floor. The conduit is fastened to the brush and is connected to a receptacle 64 by means of conduit 65, flexible conduit 66, and valve 67. This valve is operable by handle 68, which is mounted at the top of the casing.

The apparatus is conditioned for removing old wax and accumulated dirt from a floor by moving the handle from its left hand position, Fig. 1, to a right hand position. This action causes the lower portions of the brushes to be lowered below the surfaces of pads 11 and 12. The operator then opens valve 67 to the amount necessary for obtaining the desired distribution of cleaning fluid, and the cleaning operation is accomplished by moving the apparatus over the floor as the cleaning fluid drips to the floor. The cleaning fluid is spread by brush 32, and at the same time the floor is scrubbed by the dry brush 31. After the floor has been cleaned by the use of the apparatus in this manner, handle 49 is swung to the position illustrated in Fig. 1 with the result that the carrier and brushes are raised by the action of springs 35 and 36. The operator then opens valve 27 to permit waxing or oiling material to be distributed to the upper surface of pad 11. The treating material is applied to the surface of the floor by this pad, and polishing is accomplished as pads 11 and 12 are reciprocated over the surface of the floor.

Various changes and modifications in construction, form and relative arrangement of parts, which will now appear to those skilled in the art, may be made without departing from the scope of the invention. For example, either the brushes or the pads may be made to replace the other in functional position, and the manipulative means for conditioning the apparatus either for cleaning or polishing may be independent of the handle by which the apparatus is pushed over a floor. Reference is, therefore, to be had to the appended claims for a definition of the limits of the invention.

What is claimed is:

1. In apparatus of the character described, a casing, a receptacle for containing liquid material, a pad of absorptive material supported at the underside of said casing, means for distributing liquid material from said receptacle to said pad, polishing means mounted at the underside of said casing, said pad and polishing means normally supporting said casing on a surface to be treated, a carrier displaceably mounted for vertical movement with respect to said casing and said pad and polishing means, brushes mounted on said carrier and positionable thereby to above and below the operative surfaces of said pad and polishing means, a second receptacle containing liquid material, means for discharging liquid material from said last named receptacle adjacent one of said brushes, means for positioning said carrier and brushes to place said brushes in position of operative use and of support for said casing with said pad and polishing means above said brushes in non-use position and out of their normal casing-supporting position, and means

attached to said casing for manipulating the positioning means.

2. In apparatus of the character described, a casing, a rubbing pad fastened to the underside of said casing, a carrier adjacent to said rubbing pad and mounted in said casing for vertical displacement, a cleaning brush supported from said carrier, said cleaning brush being adapted to be located with its operative surface above or below the operative surface of said rubbing pad depending upon the position of said carrier, springs cooperating with said casing and said carrier and normally holding said carrier in an elevated position, means including a lever pivotally mounted on said casing for actuating said carrier against the action of said springs to displace said carrier to a position in which said brush will bear upon a floor surface, a handle pivotally mounted on said casing, and means controlled by said handle for positioning said carrier and said brush relative to said pad. 20
